UNITED STATES PATENT OFFICE

HOWARD M. BARBER, OF PAWCATUCK, CONNECTICUT, ASSIGNOR TO C. B. COTTRELL & SONS COMPANY, OF WESTERLY, RHODE ISLAND, A CORPORATION OF DELAWARE

ROTARY WEB-PRINTING PRESS

Application filed November 10, 1928. Serial No. 318,507.

The object of my present invention is to provide a rotary web printing press which is especially designed for so called bag printing; whereby the printed web which may be 5 of thin or loosely woven material, such as burlap, will have the successive printings thereon in one or more colors, spaced at different distances apart according to the length of the sheets which are to be cut from the 10 web.

My invention comprises an impression cylinder of a predetermined diameter and co-acting form cylinders of larger or smaller corresponding diameters, which form cylinders I will hereinafter designate as change form cylinders as they may be of any desired corresponding diameters within a reasonable range and not necessarily sub-multiples of the diameter of the impression cylinder, to 15 suit bag blanks or sheets of different lengths; the change form cylinders of one diameter for one predetermined length of sheet being readily substituted for change form cylinders of another diameter for another predetermined length of sheet, without rebuilding 20 the press.

My invention further comprises, in a four color rotary web printing press, four change form cylinders of the same selected diameter 25 and two impression cylinders, each adjustable for coaction with two of the change form cylinders; means being provided for moving each impression cylinder into position to coact with its respective change form cylinders and for locking the impression cylinders in their adjusted positions; an adjustable registering gear which coacts with the impression cylinders, being also provided for ensuring the synchronous action of the two 30 impression cylinders.

A practical embodiment of my invention is represented in the accompanying drawings, in which

Fig. 1 represents a detail side elevation illustrating the impression cylinders adjusted for coaction with relatively large change form cylinders of the same diameter.

Fig. 2 represents a similar view illustrating the impression cylinders adjusted for co-

action with relatively small change form cylinders of the same diameter.

The main frame of the press is denoted by 1, in each side of which frame the two impression cylinders 2 and 3 of the same desired diameter have their shafts 4 and 5 mounted in horizontally adjustable bearings 6 and 7, located in the same horizontal plane. These impression cylinders present an unbroken impression surface for the traveling 60 web.

In Figure 1 four change form cylinders 8, 9 and 10, 11 of the same relatively large diameter are illustrated, two cylinders being driven from and coacting with the impression cylinder 2 and the other two cylinders being driven from and coacting with the impression cylinder 3. In Figure 2 four change form cylinders 12, 13 and 14, 15 of the same relatively small diameter are illustrated, two cylinders being driven from and coacting with the impression cylinder 2 and the other two cylinders being driven from and coacting with the impression cylinder 3.

The two selected change form cylinders for each impression cylinder are located in a vertical plane at equal distances above and below the plane of movement of their coacting impression cylinder to permit its simultaneous coaction with both of the form cylinders. The circumference of each change form cylinder is herein shown as twice the length of the sheet to be subsequently cut from the web.

Fixed bearings 16, 17 and 18, 19 are provided in each side of the main frame for mounting either the shafts 20, 21 and 22, 23 of the large change form cylinders 8, 9 and 10, 11 shown in Fig. 1, or the shafts 24, 25 and 26, 27 of the small change form cylinders 12, 13 and 14, 15, shown in Fig. 2.

While I have shown change form cylinders of two diameters in the two figures, it is to be understood that these change form cylinders may be of any desired diameter, not necessarily a sub-multiple of the impression cylinder, so that successive printings on the web may be spaced at any desired distance apart, within reasonable limits, to suit sheets of different lengths to be cut from the printed web.

The inking mechanisms for the change form cylinders are denoted by 28, 29 and 30, 31, said inking mechanisms being mounted and positioned in their respective stands 32, 33, adjustable along the base of the main frame to bring the inking mechanisms into and out of coaction with their respective change form cylinders.

The impression cylinders 2 and 3 are connected for synchronous action, through the registering gear 34 which is adjustable along a plane at right angles to the plane of movement of the impression cylinders; the shaft 35 of the registering gear being movable along alined vertical slots 36 in brackets 37 carried by the main frame, a nut 38 serving to lock the registering gear in its adjusted position.

The impression cylinder 2 is shown as moved in a horizontal plane into position to simultaneously coact with its two change form cylinders by the following means:

A hand wheel 39 has its stud shaft 40 provided with a gear connection 41, 42, 43 with a cross shaft 44 having a worm and gear connection 45, 46 at each side of the frame with a screw shaft 47 engaging the bearing 6 which is slidable along a guideway 48. A set screw 49 is arranged in position to engage the bearing 6 and lock it in its adjusted position.

The impression cylinder 3 is shown as moved into position to simultaneously coact with its two change form cylinders by the following means:

A handle 50 has its stud shaft 51 provided with a gear connection 52, 53, 54 with a cross shaft 55 having a worm and gear connection 56, 57 at each side of the frame with a screw shaft 58 which engages the bearing 7 slidable along the guideway 59. An adjusting screw 60 is arranged in position to engage the bearing 7 and lock it in its adjusted position.

A change gear drive is provided for the impression and change form cylinders, which change gear drive is shown in the accompanying drawings as including in each form, a change gear of the same diameter as the selected change form cylinders. The rocking support for the change gear is denoted by 61 and it carries a stud shaft 62. This stud shaft serves in Fig. 1 as a mounting for the change gear 63 and in Fig. 2 as a mounting for the change gear 64.

The means which I have shown for rocking the supports 61 to bring the selected change gear into its driving connection with the impression cylinder gear 65 is shown as a hand wheel 66 having its cross shaft 67 connected at each side of the machine through bevel gears 68, 69 with a worm shaft 70 having a worm 71 meshing with a gear segment 72 carried by the rocking support 61.

The web is shown as passing around suit-

able rollers 73, 74 to and around the impression cylinder 3 and from thence around a suitable roller 75 to and around the impression cylinder 2. From thence the web passes around suitable rollers 76, 77, to the delivery point.

The drive for either the change gear 63 or the change gear 64 is shown as a gear 78 on the shaft 79 which meshes with a gear 80 on the shaft 81. A gear 82 on this shaft 81 meshes with a gear 83 on the stud shaft 62.

The rocking support at each side of the machine may be locked in its adjusted position by means of a bolt 84 projecting through an elongated slot 85; a locking nut 86 being provided for said bolt.

In the accompanying drawings the web is printed in four colors and is shown as passing around both of the impression cylinders 2 and 3 to be printed upon by the four change form cylinders. However, it will be seen that the web may be printed in two colors only by passing it around either the impression cylinder 2 or the impression cylinder 3 to be printed upon by the change form cylinders coacting with the selected impression cylinder.

It is to be understood that when the form cylinders of one diameter are changed for form cylinders of another diameter, the gears which drive the impression cylinders and through them the form cylinders, are also correspondingly changed.

It is evident that various changes may be resorted to in the construction, form and arrangement of the several parts without departing from the spirit and scope of my invention, hence I do not intend to be limited to the particular embodiment herein shown and described, but what I claim is:

1. In a multi-color rotary web printing press, two impression cylinders, each adjustable for coaction with change form cylinders of the same diameter selected from change form cylinders of different corresponding diameters, means for moving the impression cylinders in opposite directions into positions to coact with their respective selected change form cylinders and adjustable means connecting the impression cylinders for synchronous action.

2. In a multi-color rotary web printing press, two impression cylinders, each adjustable for coaction with change form cylinders of the same diameter selected from change form cylinders of different corresponding diameters, means for moving the impression cylinders in opposite directions into positions to coact with their respective selected change form cylinders, impression cylinder gears, and an adjustable registering gear engaging both impression cylinder gears.

3. In a multi-color rotary web printing press, two impression cylinders, each adjustable for coaction with change form cylinders of the same diameter selected from change

- form cylinders of different corresponding diameters, means for moving the impression cylinders in opposite directions into positions to coact with their respective selected change form cylinders, means for locking the impression cylinders in their adjusted positions, impression cylinder gears, and an adjustable registering gear engaging both impression cylinder gears. 5
- 10 4. In a four color rotary web printing press, two impression cylinders, each adjustable for coaction with two change form cylinders of the same diameter selected from change form cylinders of different corresponding diameters, means for moving each impression cylinder into position to coact with its selected change form cylinders and adjustable means connecting the impression cylinders for synchronous action. 15
- 20 5. In a four color rotary web printing press, two impression cylinders, each adjustable for coaction with two change form cylinders of the same diameter selected from change form cylinders of different corresponding diameters, means for moving each impression cylinder into position to coact with its selected change form cylinders, impression cylinder gears, and an adjustable registering gear engaging both impression cylinder gears. 25
- 30 6. In a four color rotary web printing press, two impression cylinders, each adjustable for coaction with two change form cylinders of the same diameter selected from change form cylinders of different corresponding diameters, means for moving each impression cylinder into position to coact with its selected change form cylinders, means for locking the impression cylinders in their adjusted positions, impression cylinder gears, and an adjustable registering gear engaging both impression cylinder gears. 35
- 40 7. In a four color rotary web printing press, two impression cylinders, each adjustable for coaction with two change form cylinders of the same diameter selected from change form cylinders of different corresponding diameters, each two selected change form cylinders being located at equal distances on both sides of a plane passing through the axis of rotation of their impression cylinder, means for moving each impression cylinder along said plane into position to coact with its selected change form cylinders, impression cylinder gears, and a registering gear engaging both impression cylinder gears and adjustable along a plane at right angles to the movement of the impression cylinders. 45
- 50 8. In a four color rotary web printing press, two impression cylinders mounted in the same horizontal plane and each adjustable for coaction with two change form cylinders of the same diameter selected from 55
- 55 65
- change form cylinders of different corresponding diameters, each two selected change form cylinders being located in a vertical plane at equal distances above and below the horizontal plane passing through the axis of rotation of their impression cylinder, means for moving each impression cylinder along said horizontal plane into position to coact with its selected change form cylinders, impression cylinder gears, and a vertically adjustable registering gear engaging both impression cylinder gears. 70
- 75
- 80 In testimony, that I claim the foregoing as my invention, I have signed my name this 8th day of November, 1928.
- 85 HOWARD M. BARBER.
